FEEDING APPARATUS FOR STRAIGHTENING MACHINES

Dwight J. Perdue and Clarence E. Richards, Canton, Ohio, assignors to Republic Steel Corporation, Cleveland, Ohio, a corporation of New Jersey

Application January 24, 1947, Serial No. 724,144

9 Claims. (Cl. 198—127)

1

The present invention relates to a feeding apparatus for a straightening machine, and particularly for a machine adapted to straighten elongate cylindrical work pieces, such as bars, pipes or tubes.

Such work pieces are customarily straightened during the production thereof by passing them through a straightening machine, which consists essentially of a pair of driven rolls respectively associated with idler rolls and so arranged as simultaneously to rotate and axially to advance the work piece and a pressure roll which accomplishes the straightening operation. At the relatively high speeds of operation now in use in manufacturing such articles on a commercial scale, such as in steel mills, for example, bundles of somewhat bent or crooked work pieces of this kind are placed on a rack located at one side of and parallel with the entry or feed table. On this rack the banding wires are cut and the work pieces rolled onto skids over the entry table. The entry tables are provided with driven rollers normally located below the top of the skids. After a work piece is moved onto these rollers, the table is raised and the workpiece is moved by the driven rollers into position for entering into the bending rolls of the straightening machine. Apparatus for performing this operation is shown and described, for example, in the Woodard Patent No. 1,738,340, granted December 3, 1929.

The actual entering of a bar or pipe into the straightening machine has been to a certain extent a manual operation and is in practice very dangerous, due to the fact that the bar or pipe is moved forwardly and guided by the operator's hands into the throat of the rotating bending rolls, and the operator does not release the work piece until he feels the rolls of the straightening machine gripping it. At this instant these rolls start to impart a rotating movement to the work piece, theoretically about its axis, but due to the crookedness of the work piece, the operator must remove his hands very rapidly and step out of the whip zone of the free portion or end of the work piece. In some instances bending roll equipment for straightening bars or pipes of small diameter do not have positively driven rollers associated with the entry tables. Such apparatus are usually provided with guarded entry troughs into which the work pieces are successively dropped and hand-entered into the throat of the bending rolls. On all sizes of straightening machines, this hand-entering operation is dangerous and often operators with

2

many years of experience have become careless and have had their hands or clothing caught by the rotating work pieces, causing serious accidents.

5 A primary object of the present invention is to render the hand operation of entering the work pieces into the straightening machine unnecessary, so as positively to prevent the liability for accidents in connection with this operation.

10 10 A further and more detailed object of the present invention is to provide in conjunction with a work table and a positively driven feed roller associated therewith, means for gripping a work piece against the surface of such feed roller and preferably also for centering such work piece in a manner such that the operation of feeding the leading end of the work piece into the straightening machine associated with the feed table apparatus will be entirely automatic, at least insofar as the elimination of the manual feeding operation is concerned.

15 15 A further detailed object of the invention in this respect is to provide a feed roller of concave outer contour, which will tend to center the work pieces being fed thereby and with which is associated an idler roller having means to move it to and from an operative position in which it may grasp a work piece in conjunction with and between it and the positively driven roller. In 20 one specific embodiment of the invention this idler roller is formed with an outer contour substantially complementary with that of the driven roller, while in another embodiment of the invention hereinafter described the idler roller is mounted for free floating or self-centering movement in respect to the driven roller, the idler specifically illustrated in connection with this form of the invention being cylindrical in outer contour.

25 25 30 35 40 45 Further detailed objects of the invention include the provision of automatic means for moving the idler roller to and from its operative position, the provision of alternatively usable means of a manually operable type for effecting the same results, and in conjunction with such manually operable means, the provision of counter-balancing means to enable the manual operation to be accomplished with a minimum of effort.

50 55 A further object of the present invention is to provide a guide means preferably moving with the idler roller for assisting in the centering operation of a work piece, which is also effected to some extent by the provision of a concave contour for the driven roller.

Other and more detailed objects of the present invention will become apparent from the following specification and appended claims when considered in connection with the accompanying drawings, in which:

Figure 1 illustrates, substantially in plan view, apparatus embodying one form of the present invention in conjunction with a straightening machine, the latter being shown solely diagrammatically;

Fig. 2 is a view, substantially in elevation, of many of the parts of Fig. 1, the straightening machine per se being omitted;

Fig. 3 is a fragmentary plan view on an enlarged scale of that portion of the apparatus of Figs. 1 and 2 to which the structure including the present invention is applied, showing the relationship of the parts in their operative position;

Fig. 4 is a view, substantially in elevation, of the parts shown in Fig. 3;

Fig. 5 is a view, substantially in transverse vertical section, taken on the line 5—5 of Fig. 4;

Fig. 6 is a diagrammatic view illustrating the fluid or air pressure cylinder for moving the idler roller to and from its operative position and a valve means associated therewith;

Fig. 7 is a fragmentary plan view of a modified form of the invention, wherein a manually moved and floating idler roller is employed;

Fig. 8 is a view in front elevation of the apparatus of Fig. 7;

Fig. 9 is a view in transverse vertical section taken substantially on the line 9—9 of Fig. 8 and showing the idler roller in its operative position;

Fig. 10 is a similar view in transverse vertical section taken substantially on the line 10—10 of Fig. 8; and

Fig. 11 is a fragmentary detailed view principally in elevation and taken substantially on the line 11—11 of Fig. 8 showing the relation of the centering guide to the driven roller.

Turning now to the accompanying drawings, and particularly Figs. 1, 2 and 5, there is shown an entry table generally designated as 1, which may be constructed in any usual manner, principally from structural shapes as shown or in any way desired, including those taught in the prior art. The particular construction of the entry table and the skid means upon which the work pieces are supported prior to being delivered in sequence onto the entry table apart from the present combination forms per se no part of the present invention.

As particularly shown in these figures the entry table 1 is supported by a plurality of vertically disposed angle members 2, which may be set in the floor or other support generally designated at 3 and which may in practice be concrete or any other suitable material. The angle members 2 may be connected by longitudinally extending members 4 suitably secured thereto as by bolts, rivets or the like or by welding, and also may be connected by transversely extending structural members 5. Supported upon the members 5, intermediate the longitudinal members 4 or the angles 2, may be a panel member 6, forming with the members 4 a trough, which may be lined by removable side members 7 and a bottom member 8. The members 7 and 8 may be of some material capable of withstanding the wear and tear due to the whip of the trailing end portions of the work pieces being handled. Suitably secured to the structure hereinabove

described are laterally extending skid bars 9 forming a rack-like table surface 10, upon which a plurality of work pieces as shown at 11 may be located prior to being moved one at a time into the center portion of the entry table in position to be moved forwardly in sequence into the straightening apparatus.

At spaced intervals longitudinally of the entry table 1 means may be provided for preventing the whip of the bars from being effective outside a restricted area and for confining this whip to a predetermined space principally within the trough-forming elements 7 and 8. Such means comprise a plurality of curved bracket or guard members 12, Fig. 5, each suitably secured as by an angle member 13 to one of the upright angle members 2 and including a portion overlying the trough formed by the members 7 and 8. Pivotally secured to the outer ends of each of the bracket members 12, there may be a finger guard detent member 14, which is free to move in respect to the end of the associated member 12 about the axis of a pivot pintle 15. The lower ends of the members 14 are beveled as best shown in Fig. 5, so as to complete the encirclement of the space into which a work piece 11 is moved for feeding it into the associated straightening apparatus. The center of gravity of each member 14 is such in respect to its pivotal point that it will normally occupy a position substantially as shown in Fig. 5, but may be moved in a clockwise direction from this position to admit one work piece 11 at a time as it is rolled from the rack surface 10.

Suitably disposed at spaced intervals longitudinally of the entry table 1 are a plurality of positively driven rollers 16, 17 and 18, any desired number being used, although but three are shown on the accompanying drawings. These rollers are suitably supported by having rigid therewith pivot pins or shafts journaled in suitable bearing means 19. The forward ends of the shafts for the rollers 16-18 inclusive are extended outwardly from their associated bearings and carry suitable means for driving the rollers, here shown as sprocket wheels, one of which is illustrated in Figs. 4 and 5 at 20. These sprocket wheels are suitably connected by sprocket chains 21 and 22 and are driven by suitable means shown as a sprocket chain 23, a speed reducing gear mechanism generally indicated at 24 and direct connected motor 25. It will be understood that while there is shown herein one particular set of mechanisms for driving these rollers, any other equivalent mechanism for this purpose might be used, including that shown and described, for example, in the Woodard patent, No. 1,738,340, above referred to. This mechanism per se forms no part of the present invention.

As shown, each of the rollers 16 to 18 is concave in its outer contour, thus tending to center a work piece freely resting thereon by moving said work piece in a direction parallel to the axis of the respective roller.

As shown in Fig. 1, the apparatus thus far described is arranged to be associated with a straightening machine generally designated by the reference character 26, to which the work pieces are consecutively fed, one of such work pieces at a position about to enter the rolls of the straightening machine being shown at 27, Fig. 1. The straightening machine 26 may be of any ordinary construction and include driven rolls 28-29, respectively associated with idler

rolls 30 and 31 and a pressure roll 32, which straightens the work pieces as they are consecutively rotated and drawn through the straightener by the combined action of the rolls 28-30 and 29-31, straightening machines of this general character being well known and in common use.

In accordance with the present invention and particularly that form thereof shown in Figs. 1 to 6, inclusive, there is provided an idler roller 10 for cooperation with one of the positively driven rollers 16 to 18, preferably that roller which is nearest to the straightening machine of the group associated with the entry table, i. e., the roller 16 in the present case. This idler roller is adapted 15 to cooperate with its associated driven roller in gripping a work piece therebetween at the operative position of the idler roller. At this operative position the idler roller is mounted upon an axis which is preferably substantially parallel 20 with the axis of the associated driven roller, i. e., the roller 16, in this case horizontal. The idler roller is arranged for bodily movement between an operative position as just described and an inoperative position in which it is wholly out of 25 the way of work pieces being moved onto the entry table or being carried from the entry table subsequent to their leading end being gripped by the rollers of the straightening machine.

As shown in Figs. 1 and 6, inclusive, there is thus provided an idler roller 33, which is shown in its operative position in Figs. 1 to 5 inclusive and in dotted lines in Fig. 4 at its inoperative position as shown at 34. The idler roller 33 has a convex contour or shape, substantially complementary with the shape or contour of the associated driven roller 16 (see particularly Fig. 5), so as to cooperate with that driven roller to engage therebetween a work piece irrespective of some lateral displacement of that work piece from a centered position on that driven roller, which may occur due to a crooked shape of the work piece.

Means are provided for supporting the idler roller 33 and for moving it bodily between its operative and inoperative positions as aforesaid. For this purpose there is shown in Figs. 1 to 5 a member 35 formed as an offset arm extending from a bearing portion 36 for this member. At its outer end the member 35 has a pair of depending portions 37 arranged to support axial pintle portions 38 of the idler roller 33, the depending portions 37 being connected by a web 39 as shown in Figs. 4 and 5. The member 35 may be keyed or otherwise suitably secured to a short shaft 40, which is journaled in a stationary bearing bracket 41, in turn carried by a bracket 42, which is secured to the framework of the entry table. At its outer end, i. e., outside the bearing bracket 41, the shaft 40 has keyed or otherwise suitably secured thereto an actuating arm 43 by which the member 35 and the idler roller 33 carried thereby may be moved about the axis of the shaft 40.

While it is contemplated that these parts may be operated either manually or automatically, there is shown in the form of the invention illustrated in Figs. 1 to 6 an automatic means for effecting this operation. As shown, this means comprises a fluid or air pressure cylinder 44, which is pivoted at its lower end at 45 to a suitable supporting pillar or base 46, so as to permit of the necessary movement of the cylinder incident to lost motion for the outer end of the arm 43, to which the piston of this cylinder 44

is pivoted at 47. Suitable valve means may be provided as diagrammatically illustrated in Fig. 6 for the supply and exhaust of fluid or air pressure to the opposite ends of the cylinder 44. As shown in that figure a valve means is provided as illustrated diagrammatically at 48 and which may be operated by a suitable foot pedal 49, under the control of an operator, to control the flow of fluid or air pressure from a supply line 50 for such pressure to and from the opposite ends of the cylinder 44 through lines 51 and 52 communicating between the valve means 48 and the cylinder, a suitable exhaust passage diagrammatically illustrated at 53 being associated with the valve means 48 in the usual manner. In view of the necessary movement of the cylinder 44 about its pivot 45, some part or parts of the lines 51 and 52 will in practice be made flexible, and of such a nature and character as to permit of this movement. It will be understood that the valve means 48 may be of any conventional type and is so located, preferably adjacent to the entrance to the straightening apparatus 26, as to permit the operator to perform his duties in an efficient manner.

The operation of the device in Figs. 1-6 should be obvious from the above description. Starting with the parts in the position of Fig. 5, the valve means 48, Fig. 6, is first moved to admit fluid or air pressure to the lower end of the cylinder 44 and exhaust such pressure from the upper end thereof, thus extending the piston from the cylinder and moving the crank arm 43 in a clockwise direction as seen in Figs. 2 and 4. This moves the idler roller 33 from its full line or operative position to its dotted line or inoperative position, shown at 34, in Fig. 4. A work piece may then be moved onto the entry table and into the trough portion thereof formed by the parts 7 and 8. At this position it is carried to the left as seen in Figs. 1 and 2 by the rollers 16, 17 and 18, or some of them. After the leading end of this work piece has passed the roller 16 and approaches the position shown for the work piece 27, Fig. 1, pressure to the cylinder 44 is reversed by the operation of the valve means 48, causing the idler roller 33 to move downwardly and to grip the work piece between it and the roller 16. Due to the configuration of these rollers, the work piece has been substantially centered meanwhile, so that it moves forwardly in a substantially centered position. However, irrespective of the centering, it is resiliently gripped between the idler roller 33 and the driven roller 16, and substantially positively moved forwardly into the entrance rollers 28-30 of the straightening machine 26, as shown for the work piece 27, Fig. 1. After the leading end of the work piece has been gripped by the rollers 28 and 30, it is rotated and simultaneously drawn forwardly through the straightening machine, being straightened incident to its movement by the pressure roller 32 thereof. The idler roller 33 may immediately thereupon be moved upwardly out of contact with the work piece during this actual straightening operation, or, if desired, it may be maintained in its operative position under the resilient action of the fluid or air pressure cylinder 44. The valve means 48 is usually arranged to maintain the idler roller in its inoperative position, corresponding to the full line position of the lever 49. When this lever is depressed, against the force of a resilient means (not shown) associated with the valve means 48, the idler roller is moved downwardly by the cylinder 44 to its operative position. Upon release

of pressure on the lever 49, the resilient means is immediately effective, through the means described, to move the idler roller 33 to its inoperative position. It is usually contemplated that this cylinder will be operated by pneumatic pressure. Alternatively, however, a hydraulic pressure cylinder could be used in this connection, but if so, means are preferably provided associated therewith such as a conventional air bell (not shown) to afford some resiliency to the action of the cylinder. In any event, the apparatus operates in a sufficiently positive manner to insure the desired results without requiring a manual feeding operation as was formerly necessary.

Referring now to the form of the invention shown in Figs. 7 to 11, inclusive, there is illustrated an apparatus including a work table generally indicated at 54, this table not being disclosed in detail as to its construction, but merely indicated in a diagrammatic manner. The table comprises elongate confining means in the form of a part spiral shown at 55, Figs. 9 and 10, which may be employed for permitting the introduction of a work piece, while at the same time confining the whip zone thereof in such a way as to prevent harm to surrounding apparatus and to the attendant personnel, an entrance opening or part 56 being provided for the introduction of work pieces into the center part of the spirally confined zone.

The entry table 54 may be interrupted to provide a space indicated at 57 in which a moving means for the work pieces may be interposed. Such means includes a positively driven roller shown at 58, which has suitable pintle portions received in bearings 59 carried by a supporting structure generally indicated at 60. The driven roller 58 may be reentrant or concave in its outer contour in the manner heretofore described for driven rollers 16-18.

Means are provided for driving the driven roller 58, here shown as a sprocket chain 61, a speed reducing gear mechanism 62 and a suitable motor 63 directly connected to the mechanism 62.

Also associated with the apparatus shown in these figures is an auxiliary supporting means for the work pieces during their passage across the space 57, this means comprising a lateral arm 64, which may be pivoted at 65 to an upstanding bracket 66 carried by the supporting structure 60. The other end of the arm 64 may be guided in a suitable inverted U-shaped guide member 67, as shown in Figs. 7 and 9. The arm 64 has a depending stud portion substantially centrally thereof, which is vertically aligned with a threaded stud 68 which passes through a part of the supporting structure 60. Threaded on the stud 68 above the web of the supporting structure 60, as shown in Fig. 9, is a nut 69, which serves as an abutment for the lower end of a compression spring 70, extending between the upper side of this nut and the underside of the arm 64 and surrounding a portion of the stud 68 extending upwardly through the nut 69, and the aligned stud depending from the arm 64. By controlling the position of the nut 69 on the stud 68, the position of the arm 64 may be adjustably controlled to accommodate work pieces of different weight or size.

Associated with the driven roller 58 is an idler roller 71, which is arranged to rotate freely about its axis. The roller 71 is substantially cylindrical in its outer contour and is arranged as herein-after particularly described to cooperate with the

driven roller 58 to grip therebetween a work piece as shown at 72, Figs. 8 to 10.

Means are provided for supporting and for bodily moving the idler roller 71 to move it between its operative position shown in full lines in several figures and an inoperative position shown in dotted lines at 73, Fig. 8. For this purpose, a supporting member 74 is provided which carries the roller 71 in a manner more particularly hereinafter described. The supporting member 74 is secured to or formed as a part of a lever arm 75, which is journaled for movement about the axis of a pintle 76. This pintle is formed as a bolt having different diameters at different portions thereof and having a relatively small diameter portion passing through a bearing portion 77 of an arm 78 extending to the supporting structure 60 and carried thereby. A larger diameter portion of the pintle 76 passes through a bearing sleeve or bushing 79 in a hub portion of the arm 75 and has a larger diameter head 80 at its inner end, as shown in Fig. 9. A nut 81 is threaded on the outer end of the pintle 76 to hold the parts in assembled relation.

While it is contemplated that automatic means could be provided for moving the supporting member 74 to move the roller 71 between its operative and inoperative positions as above set forth, we have shown for this purpose a manual

means in Figs. 7 to 10. This means comprises a long extension 82 of the lever 75 having hand grip part 83 at its outer end. In order to facilitate the movement of the parts by the hand lever thus provided, the apparatus may be equipped with a suitable counterweight as by providing on the hub portion of the lever 75 an outwardly extending arm 84 to some part of which a suitable counterweight 85 may be secured. It is contemplated that the counterweight may be attached at a distance outwardly on the arm 84 such as to be of the maximum benefit in use. The usual arrangement is such that the counterweight will be effective to move the idler roller 71 to its inoperative position when the hand lever 83 is released. For this purpose the arm 84 may be provided with a plurality of holes, through any of which a bolt 86 securing the counterweight to the arm may pass.

Suitable stop means may be provided for adjustably predetermining the limit of movement of the idler roll 71 toward its operative position. For this purpose the bearing portion 77 of the arm 78 may be provided with a rigid extension 87 against which a bolt 88 threaded through a flange of the lever arm 75 is adapted to abut. The adjustment may be effected by threading the bolt 88 different distances through the web or flange of the lever 75, and the adjustment secured by a suitable lock nut 89.

Means are provided for a floating connection between the supporting means 74 and the roller 71, so as to permit the roller to be self-centering in operation. For this purpose the roller 71 is freely rotatable about a pintle shown horizontal in the view in Fig. 9 and carried by a bracket 90. The bracket 90 is pivoted to the supporting means 74 about a pintle 91, which extends transversely in respect to the direction of the axis of the roller 71. Considered from another point of view, the roller 71 may be self-adjusting by movement in a substantially vertical plane (considering the roller in its operative position), which plane contains the axis of the roller 71. In this way, the roller may cooperate with the reentrant or concave configuration of the driven roller 58, so as to

grip a work piece therebetween in various positions of this work piece including the central position shown in Figs. 9 and 10.

An additional function of the floating connection for the idler roller 71 is that, upon the work piece being grasped by the rollers of the straightening machine and rotated thereby, the portion of the work piece grasped between the driven roller 58 and the idler roller 71 will be correspondingly rotated. This will be effective through the frictional engagement of the idler roller and the work piece to move the idler roller laterally as seen in Figs. 9 and 10 about the center of the pintle 91, so as in effect to "kick off" the engagement of the idler roller with the work piece, once it has performed its initial guiding function.

As particularly shown in Figs. 9 and 10, when the apparatus is employed in conjunction with a work piece of the size and type for which it is particularly designed, as shown for example at 20 72, the upper work piece-contacting surface or portion of the driven roller 58 is concave or re-entrant substantially in a manner seen in Figs. 9 and 10 and as substantially the arc of a circle, the center of which is at the center of the pintle 25 91. Thus as the work piece moves laterally or rotates, so as to "kick off" the roller 71 as aforesaid, the distance between the work piece-contacting portion of the driven roller 58 and the center of the pintle 91 about which the roller 71 30 may move is constant. This in practice assists in the desired operation of the apparatus which includes the "kick off" as aforesaid.

While the free floating roller construction is only shown in connection with Figs. 7 to 10, it is contemplated that this construction could readily be adapted to the form of the invention shown in the preceding figures; or conversely, the form of idler roller shown at 33 in the preceding figures could be adapted for use in conjunction with the 35 manually operated apparatus shown in Figs. 7 to 10. Such an interchange of the constructions disclosed is to be considered within the purview of the present invention.

Also shown in connection with Figs. 7 to 11 is 40 a guiding means which could be used with either form of the invention, this guiding means comprising a bracket member 92 carried by the supporting means 74 and having a downwardly directed portion 93 seen best in Fig. 11, which has a downwardly-opening V-shaped recess therein shown at 94, effective in practice to assist in the centering or positioning of work pieces as shown in Fig. 11 at 95. The inverted V-shaped opening 45 particularly cooperates with the driven roller 58, tending to keep the work piece in the center of the concave surface of the roller. This device will ordinarily be used in connection with an apparatus handling relatively light work pieces, although it is not to be considered as inoperative with any work pieces for which the apparatus as a whole is suitable.

The operation of the device shown in Figs. 7 to 11 is essentially the same as that previously described. The bars or pipes, constituting the work 45 pieces, are successively introduced into the entry table structure through the space 56 shown in Figs. 9 and 10, and when so introduced are carried forwardly, i. e., to the left as seen in Figs. 7 and 8, toward a straightening machine such as that shown at 26 in Fig. 1, but not shown in any of Figs. 7 to 11. This forward movement may be imparted by any driving means such as that shown in Figs. 7 and 8. Several such means may be provided, although but one of such means need 50

ordinarily have associated therewith an idler or gripping roll in accordance with the present invention. It is usually preferred to have this idler or gripping roll associated with the positively driven roll nearest to the straightening machine. When the work pieces as shown at 72, Figs. 8-10, have been moved sufficiently so as to be beneath the operative position of the idler roll 71, the latter is moved downwardly by manual action, the operator grasping the hand grip portion 83 of the lever 75-82. This downward movement is continued until the work piece is gripped between the rolls 58 and 71, as seen in Figs. 9 and 10, following which the work piece is moved toward the straightening machine by the automatic drive for the driven roller 58. The idler roll 71 will conform to the position of the work piece during its forward movement even though that position is changed incident to the rotation of the work piece by the straightening machine rolls and to a curvature of the work piece. This action is permitted by the free floating movement of the idler roller 71 about the axis of the pintle 91. When no work piece is in position, the stop 88 may be set so as to prevent any undesired engagement of the idler roller 71 with the driven roller 58 and thus prevent damage to the parts under these circumstances.

While we have shown and described but two principal embodiments of our invention, it will be understood that some of the features may be interchanged therebetween as hereinabove suggested, and other variations made within the knowledge of those skilled in the art, based upon the above teachings. We do not wish to be limited, therefore, except by the scope of the appended claims, which are to be construed validly, as broadly as the state of the prior art permits.

What is claimed is:

1. Apparatus for feeding elongate, substantially cylindrical work pieces to a straightening machine, comprising a feed table for sequentially supporting said work pieces with their axes substantially in a predetermined horizontal direction, a positively driven roller associated with said feed table and rotatable about a predetermined, substantially horizontal axis perpendicular to said direction, said roller having a work piece-engaging surface which is concave in a plane section radial thereof and wherein the extent axial of said roller is a plurality of times the maximum diameter of said work pieces to be handled thereby, so as to be engageable with out-of-straight work pieces at any portion of said work piece-engaging surface, while relatively straight work pieces tend to move toward the lower center portion of said surface, means for positively driving said driven roller, an idler roller rotatable about an axis which is always in a substantially vertical plane containing the axis of said positively driven roller and which is constructed and arranged to engage a work piece to press such work piece into engagement with any part of said work piece-engaging surface of said driven roller irrespective of the out-of-straight conformation of some work pieces and what portion of said surface may be engaged thereby, means supported on one side only of said feed table for supporting said idler roller, and means operated in handling each work piece for bodily moving said idler roller substantially in a plane perpendicular to the axis of said driven roller between an inoperative position in which it is clear of a work piece that may be supplied laterally onto said feed table from the side thereof opposite that on which said idler

roller is supported and disposed over said driven roller on said feed table, and an operative position in which a work piece so disposed may be gripped between said driven and said idler rollers, so as to feed a work piece, without rotating it about its longitudinal axis, into an associated straightening machine.

2. Apparatus in accordance with claim 1, wherein said idler roller has a convex contour substantially complementary to the contour of said driven roller, such as to provide a substantial uniform clearance between said rollers when they are in position to grip a work piece therebetween.

3. Apparatus in accordance with claim 1, wherein said idler roller has a substantial cylindrical contour for its work piece-engaging surface.

4. Apparatus in accordance with claim 1, wherein said idler roller is mounted for bodily movement about a stationary horizontal axis which is located parallel to the axis of said driven roller and is spaced a substantial distance longitudinally of said feed table therefrom, and wherein said means for bodily moving said idler roller comprises a fluid pressure cylinder mechanically connected to said idler roller for bodily moving it about said stationary horizontal axis, and valve means for controlling the flow of fluid pressure to and from said cylinder.

5. Apparatus in accordance with claim 1, comprising in addition, guide means carried by said means for supporting said idler roller and bodily movable with said idler roller, said guide means tending to center a work piece being fed to the straightening machine by said rollers.

6. Apparatus for feeding elongate, substantially cylindrical work pieces to a straightening machine, comprising a feed table for sequentially supporting said work pieces with their axes substantially in a predetermined horizontal direction, a positively driven roller associated with said feed table and rotatable about a predetermined, substantially horizontal axis perpendicular to said direction, said roller having a work piece-engaging surface which is concave in a plane section radial thereof and wherein the extent axial of said roller is a plurality of times the maximum diameter of said work pieces to be handled thereby, so as to be engageable with out-of-straight work pieces at any portion of said work piece-engaging surface, while relatively straight work pieces tend to move toward the lower center portion of said surface, means for positively driving said driven roller, an idler roller rotatable about an axis which is always in a substantially vertical plane containing the axis of said positively driven roller and which is constructed and arranged to engage a work piece to press such work piece into engagement with any part of said work piece-engaging surface of said driven roller irrespective of the out-of-straight conformation of some work pieces and what portion of said surface may be engaged thereby, means supported on one side only of said feed table for supporting said idler roller, means for mounting said idler roller on the last named means so as to provide for a free floating movement of said idler roller in respect to said last named means substantially in a plane containing the axis of said idler roller, which plane is substantially vertical in the operative position of said idler roller in gripping engagement with a work piece, so that said idler roller may accommodate itself to the engaging of a work piece located at different positions in respect to said driven roller, and means operating in han-

dling each work piece for bodily moving said idler roller substantially in a plane perpendicular to the axis of said driven roller between an inoperative position in which it is clear of a work piece that may be supplied laterally onto said feed table from the side thereof opposite that on which said idler roller is supported and disposed over said driven roller on said feed table, and an operative position in which a work piece so disposed may be gripped between said driven and said idler rollers, so as to feed a work piece, without rotating it about its longitudinal axis, into an associated straightening machine.

7. Apparatus according to claim 6, wherein said idler roller has a cylindrical outer work piece-engaging surface, and wherein said means for mounting said idler roller on said last named means comprises a pivotal connection about an axis fixed in respect to said last named means and disposed above and substantially at right angles to the axis of said cylindrical surface at the operative position of said idler roller.

8. Apparatus according to claim 6, wherein said idler roller has a substantially cylindrical work piece-engaging surface, and wherein said free floating movement of said idler roller is such that when said rollers are in a position gripping a work piece, the positive rotation of said work piece, after it has been engaged by the straightening machine, will move said idler roller laterally of said work piece and out of engagement therewith.

9. Apparatus according to claim 6, wherein said idler roller has a work piece-engaging surface which is symmetrical from end to end of this roller and having a diameter at its center portion which is at least as great as the diameters of its axial end portions, and wherein said means for mounting said idler roller on said last named means comprises a pivotal connection about an axis fixed in respect to said last named means and disposed above and substantially at right angles to the axis of said idler roller, at the operative position of said idler roller, said driven roller having its work piece-engaging surface of a concavity such that when said rollers are engaged with a work piece of average size, the intersection of a substantially vertical plane containing the axis of said driven roller with the work piece engaging surface thereof will be a substantially circular segment having its center on said fixed axis of said pivotal connection between said last named means and said idler roller.
